(57) **CLAIM**

I claim the ornamental design for tool case, as shown and described.

DESCRIPTION

FIG. 1 is front end view of the tool case showing my new design;

FIG. 2 is a top plan view thereof;

FIG. 3 is a right side view thereof;

FIG. 4 is a bottom plan view thereof;

FIG. 5 is a left side view thereof;

FIG. 6 is a rear end view thereof;

FIG. 7 is a top plan view in the open position thereof; and,

FIG. 8 is a front end view in the open position thereof.
The broken line showing of screwdrivers, in FIG. 2, is for
illustrative purposes only and forms no part of the claimed
design.
